No. 698,175.

Patented Apr. 22, 1902.

W. M. COOPER.
RAILWAY CROSSING.

(Application filed Feb. 17, 1902.)

(No Model.)

UNITED STATES PATENT OFFICE.

WILLIAM M. COOPER, OF KENNEDALE, TEXAS, ASSIGNOR OF ONE-HALF TO
OSCAR R. GALLOWAY, OF FORT WORTH, TEXAS.

RAILWAY-CROSSING.

SPECIFICATION forming part of Letters Patent No. 698,175, dated April 22, 1902.

Application filed February 17, 1902. Serial No. 94,497. (No model.)

To all whom it may concern:

Be it known that I, WILLIAM M. COOPER, a citizen of the United States, residing at Kennedale, Texas, have invented certain new and 5 useful Improvements in Railway-Crossings, of which the following is a specification.

This invention relates to railway-crossings; and the object is to construct a crossing which is simple and strong and durable and which 10 will prevent the hammering or pounding of the wheels of engines and cars which is so common with railway-crossings.

Another object is to construct a crossing which will not sink in the ground when the 15 ground is wet.

Other objects and advantages will be fully explained in the following description, and the invention will be more particularly pointed out in the claims.

20 Reference is had to the accompanying drawings, which form a part of this application and specification.

Figure 1 is a plan view of my invention, illustrating a railway-crossing. Fig. 2 is a plan 25 view of the bed-casting, showing the grooves for the rails to be dovetailed in the casting, also showing the holes through the bed-casting for the various bolts and the holes for drainage purposes. Fig. 3 is a vertical section along the line α α of Fig. 1. Fig. 4 is a plan view of the rock or cement foundation, illustrating how the drainage is accomplished and showing the holes for bolts securing the 30 bed-casting to the foundation. Fig. 5 is a broken view illustrating how the rails are dovetailed into the bed-casting.

Similar characters of reference are used to indicate the same parts throughout the several views.

40 One of the defects in railway-crossings is that the ground in wet weather will yield and become slushy, so that the rails sink when engines or cars run over the crossings. This causes a constant pounding or hammering of 45 the wheels against the rails. I have remedied this by a rock or cement foundation and other fixtures mounted thereon. This foundation 1 is placed at a suitable distance below the rails. On this foundation is placed a bed-casting 2. This bed-casting is bolted to the 50 foundation by means of bolts 3, Fig. 3, showing the holes 4 for bolts 3. The bed-casting

2 has a cavity 5 in the central part thereof for a bed-plate 6. Grooves 7 are formed in the bed-casting 2, so that the ends of the rails 8 can be dovetailed into the casting, as shown in Figs. 2 and 5. The rails 8 extend to the bed-plate 6 and the ends of the rails are flush with the bed-plate, the ends of the rails being also even with the walls formed by the 60 cavity in the bed-casting. The bed-plate 6 is mounted on powerful spiral springs 9, and the bed-plate is secured to the bed-casting by means of bolts 10, which are provided with suitable nuts. Fig. 2 shows the holes 11 for 65 bolts 10. Bolts 10 run through the spiral springs 9, and by this construction the spiral springs are held in place. The bed-plate 6 is provided with elevated portions or ribs, which form continuations for the rails 8. The 70 angular ribs 12 meet the ends of rails 8 and are flush with the ends of the rails and also flush with the walls of the cavity 5. The inner ribs 13 of the bed-plate support the wheels after the wheels leave the angular ribs 12. 75 The ribs 13 leave a passage for the flanges of the wheels between the ends of the ribs 13 and the corners of the angular ribs 12. It will be noticed that the ribs 12 and 13 are formed integral with the bed-plate 6. These 80 ribs might be formed in separate pieces and bolted to the bed-plate. It will be seen that by this construction the entire bed-plate, with the ribs thereof, is capable of yielding slightly 85 when the wheels of an engine or a car strike the ribs of the bed-plate. This yielding of the bed-plate must be limited by the spiral springs 9. These springs must be made strong enough to sustain the weight of the heaviest engines. The object of having the 90 bed-plate 6 subject to yielding, is to prevent the hammering of the wheels against a rigid construction. The bed-plate will yield enough to take away the force of such hammering as there would be if the bed-plate was rigid. In 95 order to prevent this yielding of the bed-plate from taking effect on the ground, the bed-plate is mounted on spiral springs 9, which rest on the bed-casting 2. Consequently the yielding motion which is caused by tremendous weight will be exhausted against the bed-casting 2, the rock or cement foundation supporting the bed-casting. The great area 100 of the foundation as compared with the cross-

ties now in use will prevent the ground from becoming slushy by the jar of the wheels.

In order to keep the ground dry about the crossings, I have provided means for draining the crossing. Holes 14 are made through the bottom of the cavity in the casting 2, so that the water will pass through the casting 2 to the foundation 1, and the foundation has grooves 15, which will receive the water from holes 14 and conduct the water to a pipe 16. Instead of a pipe 16 any suitable means may be used for conducting away the water which may be received from the holes 14 and grooves 15.

15 Many changes in the construction of the various parts of this invention may be made without departing from the invention.

Having fully described my invention, what I claim as new, and desire to secure by Letters 20 Patent, is—

25 1. A crossing for railways comprising a yielding plate flush with the ends of rails abutting thereagainst and having elevated portions or ribs thereon for forming continuations of the rails.

2. A railway-crossing comprising a yielding plate flush with the ends of rails abutting thereagainst and having ribs thereon for forming continuations for rails and a suitable foun-

30 dation for said yielding plate.

3. A railway-crossing comprising a yielding plate flush with the ends of rails abutting thereagainst and a bed-casting forming a foundation for said plate and a support for 35 the ends of said rails.

4. A railway-crossing comprising a bed-plate having elevated portions or ribs thereon for forming continuations for rails abutting thereagainst, a bed-casting having a cavity 40 therein for said bed-plate, a plurality of spiral springs between said bed-plate and said bed-casting, and bolts running through said springs and through said bed-casting and said bed-plate for securing said plate to said 45 casting.

5. A railway-crossing comprising a yielding plate flush with the ends of rails abutting thereagainst and a bed-casting having a cavity therein for said bed-plate and forming a foundation therefor and forming a support for 50 rails abutting against said plate.

6. A railway-crossing comprising a yielding plate flush with the ends of rails abutting thereagainst and having elevated portions or ribs for forming continuations for said rails, a bed-casting having a cavity therein for said bed-plate and constituting a foundation therefor, and a stone foundation for said bed-casting.

7. A railway-crossing comprising a yielding 60 plate having continuations for rails abutting thereagainst, a bed-casting, having a cavity therein for said plate, and a stone or cement foundation for said bed-casting, said bed-casting having holes therethrough for draining 65 water out of the crossing and said foundation having grooves for conducting the water away from said holes.

8. A railway-crossing comprising a yielding plate having continuations thereon for rails 70 abutting thereagainst and a bed-casting having a cavity therein for said plate and having grooves therein for rails abutting against said plate.

9. A railway-crossing comprising a yielding 75 plate having continuations thereon for rails abutting thereagainst, a bed-casting having a cavity therein for said plate and having grooves therein for rails abutting against said plate, a stone or cement foundation for said 80 bed-casting, and means for securing said bed-casting to said foundation.

In testimony whereof I set my hand, in the presence of two witnesses, this 30th day of January, 1902.

WILLIAM X M. COOPER.
